Jean O. Reinecke, Oak Park, Ill., assignor to W. A.
Sheaffer Pen Company, Fort Madison, Iowa, a corporation of Delaware

Application April 3, 1946, Serial No. 128,233

Term of patent 14 years

(Cl. D74—1)

To all whom it may concern:

Be it known, that I, Jean O. Reinecke, a citizen of the United States, residing at Oak Park, in the county of Cook, and State of Illinois, have invented a new, original, and ornamental Design for a Reservoir Desk Stand, of which the following is a specification, reference being had to the accompanying drawing, forming a part thereof.

Fig. 2 is a top plan view of Figure 1;
Fig. 3 is a front elevational view of Figure 1;

and

Fig. 4 is a side elevational view of Fig. 3.

I claim:

The ornamental design for a reservoir desk stand, substantially as shown.

JEAN O. REINECKE.
